UNITED STATES PATENT OFFICE.

ANTON MIHELCICH, OF LOWELL, ARIZONA.

CUSPIDOR.

1,166,236.

Specification of Letters Patent. Patented Dec. 28, 1915.

Application filed July 29, 1915. Serial No. 42,655.

To all whom it may concern:

Be it known that I, ANTON MIHELCICH, a citizen of Austria-Hungary, residing at Lowell, in the county of Cochise and State 5 of Arizona, have invented certain new and useful Improvements in Cuspidors; and I do declare the following to be a full, clear, and exact description of the invention, such as will enable others skilled in the art to 10 which it appertains to make and use the same.

This invention relates to improvements in cuspidors and more particularly to closures therefor.

15 The object of the invention is to provide a cuspidor having a closure so constructed that on the movement of the cuspidor, the closure will automatically close and thus reliably prevent the contents thereof from being spilled.

Another object is to provide a device of this character which is simple in construction, efficient in operation, and cheap to manufacture.

25 With the above and other objects in view, the invention consists of certain novel features of construction, combination and arrangement of parts hereinafter more fully described and claimed.

30 In the accompanying drawings: Figure 1 is a vertical section of a cuspidor equipped with this improved closure which is shown open. Fig. 2 is a similar view with the closure closed. Fig. 3 is a rear elevation 35 with the closure open; Fig. 4 is a detail transverse section taken on the line 4—4 of Fig. 2; and Fig. 5 is a detail perspective view of the hook for securing the closure in open position. Fig. 6 is a detail plan view 40 of the locking mechanism.

In the embodiment illustrated, a cuspidor C is shown of ordinary construction having the usual flared mouth M and contracted neck N although it may be of any desired 45 form and constructed of any suitable material, preferably enameled iron to render it sanitary.

The cover 1 is shown constructed to close the mouth of the cuspidor at its lower end 50 where it merges into the contracted neck N thereof, said closure being provided with an annular flange 2 which rests on the lower end of said mouth as is shown clearly in

Fig. 2. This closure is preferably made of solid metal to render it heavy and adapt it to drop automatically into closed position and lined with rubber or other suitable fabric 1^a to insure a liquid tight joint between it and said mouth when in closed position, a metal or enameled disk 1^b being here shown on the lower face of said cover which fits within the neck N. Mounted on the outer face of said closure 1 is a bearing 3 shown in the form of strips struck out of the side edges of a plate 4 which is secured to said closure, said strips being rolled inwardly to form said bearing 3, a tongue 5 projecting in advance of said bearing and secured to said cover 1 by any suitable means, said tongue being constructed by the slitting of the plate on opposite sides thereof to form the strips from which the bearing 3 is composed. These strips 3 when rolled are spaced laterally apart to receive a pintle 6, and arranged between them is a knuckle 7 having one end inclined rearwardly and secured to the upper face of the plate 4 and which is designed to form a stop or lock for a member hereinafter to be described. The plate 4 extends transversely across the cover 80 1 and the rear end thereof projects beyond said cover and is provided with a hinged knuckle 8 adapted to be inserted between coöperating knuckles 9 carried by the complementary hinge member 10 which is secured to the inner face of the mouth M of the cuspidor, a pintle 11 connecting said hinge members by being passed through the knuckles thereof in the usual manner and whereby the cover is hingedly connected 90 with the cuspidor mouth. The hinge member 10 which carries the knuckles 9 extends preferably to the outer edge of the mouth M and is provided at its opposite sides with outstanding apertured ears 12 arranged at 95 right angles to the plate 10 and through which a pintle 13 extends. A lever 14 is carried by the pintle 13 and is here shown formed from a heavy metal rod bent intermediate of its ends with the side members 100 15 thereof arranged in contact, whereby the lever is strengthened throughout the greater portion of its length. The side members 15 diverge at one end of the lever and extend laterally substantially at right 105 angles to the body portion thereof and then

are bent and extended forwardly to form parallel arms 16 provided at their free ends with eyes 17 through which the pintle 13 passes, said eyes being here shown arranged 5 outside the ears 12 of the plate 10.

5 A coiled spring 18 is mounted on the pintle 13 and is shown constructed of a wire, the ends of which are coiled around the pintle, and between said coiled ends is a 10 loop 19 which projects forwardly and through which the lever 14 is designed to pass so that the tension of said spring is exerted to hold said lever normally downward in engagement with the cover 1 of the 15 cuspidor, the free end of said lever being designed to be engaged with the stop 7 arranged at the front end of the plate 4 so that the top cover 1 is reliably locked in closed position when the lever is so arranged, 20 a spring 18 tending to hold it in such engagement.

A substantially U-shaped loop 20 is mounted on the pivot 6 carried by the bearing 3 and is here shown formed of a piece of heavy 25 wire bent intermediately of its ends with the side members thereof coiled midway their ends to form eyes 21 through which the pintle 6 passes for connecting the loop in operative position. The free ends of the side 30 members of the loop 20 are bent laterally inward toward each other to form a cross bar 22. The front end 23 of the loop 20 and the end carrying the cross bar 22 are arranged to form the legs of the U-shaped loop 20 35 which are designed for cooperation with the lever 14 in a manner to be described, said loop 20 being designed to perform as one element of a lock or latch for securing the top 1 in open position.

40 A bracket 24 is secured to the outer face of the mouth M of the cuspidor directly under the plate 10 and is curved outwardly and upwardly with its free end projecting beyond the edge of said mouth. This bracket 45 24 is provided on said projecting end at one side edge thereof with an apertured ear 25 in which a latch 26 is fulcrumed intermediately of its ends, said latch being shown provided at one end with a hook-shaped 50 member 27 which is designed to engage the loop 23 at the front end of the member 20 when the top is in raised position as is shown clearly in Figs. 1 and 3. The lower end of this latch 26 is pivotally connected with one 55 end of a lever 28 which is fulcrumed intermediately of its ends on a bracket 29 which extends outwardly from the cuspidor C, said bracket being here shown L-shaped. This lever 28 has a floor engaging member 60 30 pivotally connected at one end thereof and here shown made in the form of a loop, the intermediate portion of which is designed to engage the floor or other support on which the cuspidor is mounted and which 65 is designed to perform the function of a

trip for releasing the catch when the cuspidor is moved, thereby disengaging said catch from the loop 20 on the top or closure 1 and permitting said cap to automatically close under the tension of the spring 18. 70 When said top is closed the free end of the lever 14 will spring into engagement with the stop 7 and lock the top in closed position, the lever resting on the cross bar 22 of the loop 20 when so disposed so that when 75 it is desired to again open the top, the front end 23 of said loop 20 is moved forwardly, causing the cross bar 22 to rise under the lever end and release it from the stop 7 and permit it to clear said stop and pass through 80 the front portion 23 of the loop 20 on the raising of the top as is shown in Figs. 1 and 3.

A hook 31 is pivotally mounted on the outer face of the mouth M of the cuspidor adjacent the bracket 24 and is designed to engage the lower end of the catch 26 for holding the top reliably in open position during the cleaning of the cuspidor, preventing it from accidentally closing by the release of the lever should the trigger or trip lever 30 be actuated.

From the above description, it will be obvious that when the top is in raised position and the loop 20 engaged with the catch 26, as shown in Fig. 3, the free end of the trip lever 30 will be positioned in engagement with the floor or other support of the cuspidor so that the cuspidor, when tilted, 95 will cause this trip to move inwardly and force the upper end of the lever outwardly, thereby moving the catch 26 a sufficient distance to disengage it from the loop 20. Immediately this occurs, the spring pressed 100 lever 14 exerting its pressure on the top 1, 105 will close said top into the position shown in Fig. 2.

I claim as my invention:

1. The combination with a cuspidor having a flared mouth, a closure hinged thereto, a catch member carried by said closure, a latch on said cuspidor for engagement with said catch when the closure is open, a lever fulcrumed intermediately of its ends on said cuspidor and pivotally connected at one end to said latch, a trigger pivoted to the other end of said lever for engagement with the support of said cuspidor for releasing said latch on the movement of the cuspidor, and a spring pressed means for forcing said cover into closed position on the release of said latch. 110

2. The combination with a cuspidor having a flared mouth, a closure hinged thereto, a catch member carried by said closure, a latch on said cuspidor for engagement with said catch when the closure is open, a lever fulcrumed intermediately of its ends on said cuspidor and pivotally connected at one end to said latch, a trigger pivoted to the other 125 end of said lever for engagement with the support of said cuspidor for releasing said latch on the movement of the cuspidor, and a spring pressed means for forcing said cover into closed position on the release of said latch. 130

- end of said lever for engagement with the support of said cupidor for releasing said latch on the movement of the cupidor, and spring pressed means for holding the parts 5 under tension when the cover is open and for forcing it to closed position on the release of said latch.
3. The combination with a cupidor having a flared mouth, a closure hinged thereto, 10 a catch member carried by said closure, a latch on said cupidor for engagement with said catch when the closure is open, a lever fulcrumed at one end on said cupidor with its free end engaged with said closure, a 15 spring mounted to exert its tension on said lever to cause it normally to engage said cover, means on said cover for engagement by said lever for locking the cover in closed position, and means for releasing said lever 20 from said locking engagement.
4. The combination with a cupidor having a flared mouth, a closure hinged thereto, a catch member carried by said closure, a latch on said cupidor for engagement with 25 said catch when the closure is open, a lever fulcrumed at one end on said cupidor with its free end engaged with said closure, a spring mounted to exert its tension on said lever to cause it normally to engage said 30 cover, means on said cover for engagement by said lever for locking the cover in closed
- position, and means for simultaneously releasing said lever and raising said cover.
5. The combination with a cupidor having a flared mouth, a closure therefor, a member secured to the outer face of said closure and having a hinge knuckle at one end and a bearing at the other, a U-shaped catch loop pivotally mounted in said bearing, a plate secured to said cupidor and 40 having hinge knuckles for co-operating with the knuckle on the cover, a pintle connecting said knuckles, laterally spaced apertured ears projecting from said plate, a lever having a bifurcated inner end, the furcations 45 thereof being pivotally engaged with said pintle, a coiled spring on said pintle having a loop engaging said lever whereby the tension of the spring is exerted to force the free lever end in engagement with the closure, a 50 latch on said closure for engagement with said catch loop, and a trip lever connected with said latch and operable on the movement of the cupidor to release said closure.
- In testimony whereof I have hereunto set 55 my hand in presence of two subscribing witnesses.

ANTON MIHELCICH.
